UNITED STATES PATENT OFFICE.

ISAAC GILES, OF NEW YORK, N. Y.

SASH-FASTENER.

SPECIFICATION forming part of Letters Patent No. 447,404, dated March 3, 1891.

Application filed March 26, 1890. Serial No. 345,405. (No model.)

To all whom it may concern:

Be it known that I, ISAAC GILES, a citizen of the United States, residing at New York, in the county of New York and State of New York, have invented a new and useful Improvement in Sash-Fasteners, of which the following is a specification.

My invention has relation to sash-fasteners, and more particularly to that class thereof which, while used for locking both sash when in their closed position, is also adapted to permit of the upper sash being lowered and of the lower sash being raised to any desired position and lock both the sash in their adjusted position; and the invention has for its principal objects, first, to provide a sash-fastener of the class described, in which the locking-bolt is operated to lock or unlock the sash by means of a bolt or spindle, which is adapted to be screwed into or out of a housing or casing secured to the top rail of the lower sash, as hereinafter fully described; secondly, to provide a sash-fastener of the class described in which the belt-operating spindle is provided with a detachable head, whereby the latter may be removed after the sash have been locked, and thus prevent any unlawful unlocking of said sash; thirdly, to provide a sash-fastener of the class described, in which means are supplied for giving an audible signal when the sash are being unlocked.

With the above objects in view my invention consists in the construction, arrangement, and combination of parts, all as herein-after fully described, illustrated in the drawings, and pointed out in the claims.

In the drawings, wherein similar letters of reference indicate like parts on each figure, Figure 1 is a perspective view of my improved sash-fastener, showing the detachable head for the operating-spindle removed therefrom. Fig. 2 is a front elevation of the same, showing the locking plate or catch engaging the operating-spindle to prevent turning of the same. Fig. 3 is a vertical longitudinal section, partly in elevation, of my device, and Fig. 3^a is a detail perspective view of one of the plates which are secured to the upper sash and are adapted to receive the end of the locking-bolt. Fig. 4 is a detail perspective view of the locking-bolt and a portion of

its operating-spindle. Fig. 5 is a like view of the locking-bolt. Fig. 6 is an elevation of a portion of the upper and lower sash, showing the manner of applying my improved fastener. Fig. 7 is a vertical longitudinal section, slightly enlarged, of my sash-fastener, showing a different arrangement of the signaling device.

In the construction of my improved sash-fastener I employ a housing or casing A, which may be of any suitable construction and have any desired configuration. In the drawings I have shown the same as being rectangular of form and as consisting of the sides a a, the top a', and the end wall a² a³. The housing or casing is left open at the bottom to permit of the assembling of the internal parts of the device, and the sides a a are provided with perforated ears a⁴ to adapt the housing to be secured to the top rail of the lower sash at any point where it will meet the rail of the upper sash, or at one side thereof, as shown in Fig. 6, so as to be opposite the side rail of the upper sash. The front wall a³ of the housing is provided with a central threaded perforation b for the reception of the threaded bolt-operating spindle B, which latter is adapted to be screwed into and out of the housing through said front wall, and thereby operate the locking-bolt, as will presently appear. In order to facilitate the turning of the spindle, I provide the same at its forward end with a milled head B'. The rear end of the spindle which lies within the housing is reduced in diameter, as at b', and has the enlarged portion b² in rear of said portion b'.

C indicates the bolt by means of which the two sash are to be locked in their closed or partially open positions. Said bolt I have shown as having the rectangular portion or head C' conforming to the configuration of the interior of the housing within which the bolt is fitted and adapted for longitudinal movement. The bolt also has the reduced cylindrical shank C², which passes through a like shaped opening c in the rear wall of the housing. The head C' of the bolt is provided with the vertical recess C³ and a like recess C⁴ at right angles thereto. The recess C³ is adapted to receive the enlarged portion b² of the operating-spindle, while the recess

C¹ receives the reduced portion b' of said spindle, the mode of fitting these parts together being clearly shown in Figs. 3 and 4.

For the purpose of supporting and guiding the bolt in its longitudinal movements, the housing is provided with a longitudinal wire or rod forming a track c', secured at its ends to the ends of said housing, while the head of the bolt is provided with a groove c², with in which lies the wire c'. By this arrangement and construction of the bolt and spindle it will be seen that when the latter is turned to the right it will be caused to advance within the casing, and thereby cause the bolt to be moved rearwardly and project the shank thereof beyond the housing and enter a suitable recess or depression in the side rail of the upper sash, thereby locking the two sash together. By turning the spindle to the left the bolt will be withdrawn partially within the housing to free the shank of the bolt from the depression in said upper sash, to free the same and allow it to be lowered or the lower sash raised any desired distance.

In order that either or both of the sash may be locked at different elevations or positions the middle or side rail, as the case may be, of the upper sash is provided with a number of depressions or recesses, before mentioned, said depressions being located at suitable distances apart.

Instead of forming the depressions within the side rail of the upper sash, which might tend to impair the appearance of the window, I preferably employ metallic plates D, having openings D' adapted for the reception of the end of the bolt, said plates being screwed or otherwise suitably secured to a rail of the upper sash, as shown in Fig. 6.

In order to provide means whereby the turning of the spindle to cause the unlocking of the sash may be prevented until desired, I make the milled head of the spindle detachable, as shown in Fig. 1, whereby it may be removed from the spindle after the latter has been manipulated to effect the locking of the sash.

The detachability of the head may be effected, for instance, by squaring the outer end of the spindle, as at d', and providing the head with a rectangular opening d, within which fits loosely the said squared end d'. The head may be attached to a chain or cord d³, secured to the housing to obviate the liability of its being lost when detached.

For the purpose of locking the spindle against rotation when it has been screwed within the casing to effect the locking of the sash, I provide a spring-actuated catch or lever E, pivoted to the front wall of the housing and having a recess e, which is adapted to take over the squared portion d' or d² of the spindle, as shown in Figs. 2 and 4.

In order that an audible signal may be given to give warning that the fastener is being tampered with, any suitable arrangement

of signaling device may be provided, said device being located either upon the outside of the housing or within the same. In either arrangement the signaling device is to be operated only when the spindle is being screwed outwardly to effect the unlocking of the sash. In Fig. 1 I have shown a gong as being located upon the outside of the housing, while a clapper-arm (which may be spring-actuated or made of spring metal) extends through an opening in the side of the housing, its inner end lying within the path of the head of the bolt, so that when the latter is being pushed rearwardly within the casing the end of the arm rests upon the head of the bolt in front of the recess C³, and when said bolt is being retracted within the casing the end of the arm will spring over the edge of the recess, and thereby cause its outer end to strike the gong. In Fig. 7 I have shown the gong located upon the inside of the housing, and in this instance I show an angular lever e', pivoted upon the inside of the housing, one end lying within the path of the head of the bolt. A leaf-spring e² is employed, secured at one end to the top of the housing, while its other end bears upon the lever. The sides of the housing are here perforated to render the alarm more audible.

Of course it will be understood that instead of the described construction and arrangement of such signaling device any other preferred construction and arrangement may be employed. It will also be understood that various modifications in the construction and arrangement of the other details of my fastener may be made without departing from the essential features thereof.

Having now fully described my invention and the manner of its operation, what I claim, and desire to secure by Letters Patent of the United States of America, is—

1. In a sash-fastener, the combination, with a suitable housing or casing, of a locking-bolt contained within said casing and adapted to be projected through one end thereof, and an operating-spindle for said bolt loosely connected with said bolt and adapted to be screwed through the other end of the housing and thereby move the locking-bolt, and a detachable head for said operating-spindle, having a circular bore from which extends a quadrangular key-slot adapted to engage a squared projection on the end of said spindle, for the purpose specified.

2. In a sash-fastener, the combination, with a suitable housing or casing, of a locking-bolt adapted to be moved longitudinally therein, and a signaling device carried by said housing or casing adapted to be operated by the bolt when the same is moved in one direction, as described.

3. In a sash-fastener, the combination, with the housing or casing, of the locking-bolt located therein and adapted to be projected through one end of said housing, said bolt being provided with the intersecting recesses

- described, and the threaded operating-spindle adapted to be screwed into and out of the casing through the other end thereof, and having the reduced portion passing through 5 one of the recesses in the bolt and the enlarged portion in rear of said reduced portion fitting within the other recess of the bolt, all combined and operating substantially as described, for the purpose specified.
- 10 4. In a sash-fastener, the combination, with the housing or casing, of a locking-bolt contained within said casing and adapted to be projected through one end thereof, and an operating-spindle for said bolt loosely connected 15 with the same and adapted to be screwed through the other end of the casing, and a locking-catch secured to the outside of the casing and adapted to engage a squared portion of the spindle to prevent its rotation, as 20 described.
5. In a sash-fastener of the character described, the combination, with a suitable lock-
- ing-bolt and its operating-spindle and disk, of an attached gong, one end of the clapper of said gong extending over the bolt or its actuating-spindle and adapted to engage a projection thereon when the same is withdrawn, thereby striking an alarm, as and for the purpose intended, substantially as described. 25
6. In a sash-fastener of the character described, having projectible bolt C², the operating screw-threaded spindle B, provided with detachable head, said spindle having quadrangular recess d² near its end, in combination with spring-controlled recessed catch E, 30 supplied with lower squared notch e, adapted to mesh with the quadrangular recess d² of said spindle and maintain it in locked position, as set forth, as and for the purpose intended, substantially as described. 35
